UNITED STATES PATENT OFFICE

113,294

DESIGN FOR A SPACE HEATER

Walter D. Teague, New York, N. Y., assignor to
American Gas Machine Company, Incorporated,
Albert Lea, Minn.

Application December 1, 1938, Serial No. 81,496

Term of patent 7 years

To all whom it may concern:

Be it known that I, Walter D. Teague, residing in the city of New York, county of New York, and State of New York, have invented a new, original, and ornamental Design for a Space Heater, of which the following is a specification, reference being had to the accompanying drawing forming a part thereof, wherein,

Figure 1 is a view in perspective of a space heater showing my new design.

Figure 2 is a plan view in reduced scale of the heater shown in Figure 1, and

Figure 3 is a view in side elevation in reduced scale of the heater shown in Figure 1.

I claim:—

The ornamental design for a space heater, substantially as shown and described.

WALTER D. TEAGUE
